UNITED STATES PATENT OFFICE.

OSCAR WINTER, OF NEW YORK, N. Y.

LATCH FOR PNEUMATIC CARRIERS.

1,223,651.

Specification of Letters Patent.

Patented Apr. 24, 1917.

Application filed May 2, 1916. Serial No. 94,922.

To all whom it may concern:

Be it known that I, OSCAR WINTER, a citizen of the United States, residing at New York, in the county of New York and State of New York, have invented a new and useful Latch for Pneumatic Carriers, of which the following is a specification.

The present invention is a latch device adapted especially for use upon a carrier used in a pneumatic tube system, and aims to provide a novel and improved device for latching the cover of the carrier in closed position so that the cover is not liable to be opened during transit.

15 When the carrier of a pneumatic tube system is in motion, the cover is at the rear end of the carrier, and the contents press against the cover, due to the momentum, and when the carrier negotiates a curve, it slows down but instantly speeds up again on reaching a straight section of the tubes. This variation in speed causes the contents of the carrier to bump or jolt against the cover and with ordinary carriers will not 20 infrequently result in the cover being forced open, which is objectionable for obvious reasons.

With the present device, the accidental opening of the carrier during transit is impossible, although the cover can be readily latched and unlatched, and the device is extremely simple and inexpensive in construction, as well as being compact and thoroughly efficient.

35 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

45 The invention is illustrated in the accompanying drawing, wherein:

Figure 1 is an end view of the carrier showing the cover latched.

Fig. 2 is a similar view showing the latch moved to released position and swung out of the way to permit the cover to be opened.

Fig. 3 is a sectional detail taken on the line 3—3 of Fig. 1, showing a portion of the carrier in elevation.

55 Fig. 4 is an enlarged sectional detail taken on the line 4—4 of Fig. 1 to illustrate the

means for holding the latch in operative position.

In the drawing, there is illustrated a typical carrier 1, which may be taken to represent any suitable carrier or container. This carrier 1 is provided with an open end adapted to be closed by a cover 2, said cover being connected one side wall of the carrier 1 by means of a strap hinge 3. A plate 4 is riveted or otherwise secured to the outer surface of the cover 2, the hinge 3 being preferably clamped between said cover and plate, and the plate 4 is provided with an outstanding headed stud 5.

70 A plate or leaf 6 is hinged to a plate or leaf 7 which is riveted or otherwise secured to that wall of the carrier 1 opposite the hinge 3, adjacent the mouth of the carrier, and the plate 6 is provided with an aperture 8 for receiving the stud 5, when the plate 6 is swung against the plate 4 of the cover 2 when in closed position. The plate 6 is provided with a bent back tongue 9 extending from one side edge thereof adjacent its hinged or basal end, said tongue being upon the inner side of the plate 6 and being disposed transversely thereof.

75 A latch or catch 10, preferably formed from sheet metal, has one end pivoted, as at 11, to the inner surface of the plate 6 adjacent its free end, the aperture 8 being located between the pivot 11 and tongue 9, and the free end of the latch has a bill 12 forming a hook movable to and from the aperture 8. 80 The bill 12 works snugly between the plate 6 and tongue 9, and the latch 10 is provided with an outstanding ear 13 at the basal end of the bill 12. Said ear 13 projects outwardly from the plate 6 at one side edge thereof, and provides a finger piece whereby the latch can be conveniently moved in one direction or the other.

85 The bill 12 is provided adjacent its free end with an aperture 14 coöperable with an aperture 15 with which the tongue 9 is provided, and a ball 16, providing a detent, is mounted within the aperture 15 and is engageable in the aperture 14. A leaf spring 17 has one end secured, as at 18, to the tongue 9 adjacent the free end of said tongue, is disposed longitudinally of the tongue, projecting in a direction opposite to the direction in which the tongue projects. The spring 17 is provided adjacent its free 90 end, which is arranged adjacent the basal end of the tongue 9, with a depression or

socket 19 receiving the ball 16, and said leaf spring 17 has a tension causing it to move toward the tongue 9, whereby to move the ball 16 against the plate 6.

The plate 6 has a stop lug 20 for limiting the movement of the latch 10 when moved to releasing position, as seen in Fig. 2, in which event the latch 10 clears the aperture 8.

10 To latch the cover 2, after it is closed, as seen in Fig. 2, with the latch 10 in released position, the plate 6 is swung over the cover 2 to overlap the plate 4, and the stud 5 moves within the aperture 8. Then, by moving the 15 finger piece 13 toward and against the edge of the plate 6, the latch 10 will be moved under the head of the stud 5, thereby holding the plate 6 assembled with the plate 4 and the stud 5, whereby the cover 2 cannot 20 be opened unless the latch 10 is released, and the plate 6 swing to open position. The latch 10 in being moved to operative position causes the free end of the latch to force the 25 detent ball 16 away from the plate 6, to permit the free end of the bill 12 to pass the ball 16, and when the aperture 14 alines the aperture 15, the ball 16 is forced into the 30 aperture 14 by the spring 17, thus holding the latch in operative position. When the latch is retracted manually, the ball 16 can yield, but the latch cannot be released accidentally while the carrier is in transit.

Having thus described the invention, what is claimed as new is:—

35 1. A carrier having a hinged cover, a member hinged to the carrier to swing against the cover when in closed position, the cover and said member being provided with interengageable means including a stud 40 carried by one of them and a latch carried by the other engageable with said stud, and a detent for holding the latch in engagement with said stud.

2. A carrier for use in pneumatic tubes, 45 having an open end, a cover and a member hinged to the carrier at opposite sides of said open end and swingable away from one another in opposite directions, said member being swingable against the cover in over- 50 lapped relation when the cover is closed, an

outstanding stud carried by the cover, said member having an aperture for receiving said stud when said member is swung against the cover in closed position, and a latch carried by said member and engageable with said stud. 55

3. A carrier having a hinged cover, said cover having a headed stud, a plate hinged to the carrier to swing against the outer side of the cover and having an aperture to receive said stud, and a hook-shaped latch pivoted to said plate and swingable into engagement with said stud. 60

4. A carrier having a cover, said cover being provided with a headed stud, a plate 65 hinged to the carrier to swing against the cover, said plate having a tongue, a latch pivoted to said plate and having a bill movable between said plate and tongue, said bill providing a hook engageable with the stud 70 under the head thereof, and a detent carried by said tongue and engageable with said bill to hold the latch in operative position. 75

5. A carrier having a hinged cover provided with a headed stud, a plate hinged to 80 the carrier to swing against the cover and having an aperture for receiving said stud, said plate having a tongue extending from one edge thereof adjacent the hinged end, said tongue being disposed transversely upon 85 the inner side of said plate, a latch pivoted to the inner side of said plate adjacent the free end thereof and having a bill working between said plate and tongue to provide a hook engageable with said stud under the head thereof, said tongue having an aperture, said bill having an aperture to register therewith, a detent ball within the first mentioned aperture, and a leaf spring secured to said tongue to press said ball against said 90 plate, the ball being engageable in the aperture of said bill to hold the latch in operative position.

In testimony that I claim the foregoing as my own, I have hereto affixed my signature 95 in the presence of two witnesses.

OSCAR WINTER.
